UNITED STATES PATENT OFFICE.

ARTHUR TREVOR DAWSON AND GEORGE THOMAS BUCKHAM, OF WESTMINSTER, LONDON, ENGLAND, ASSIGNORS TO VICKERS LIMITED, OF WESTMINSTER, ENGLAND.

GUN-CARRIAGE.

1,300,355.

Specification of Letters Patent. Patented Apr. 15, 1919.

Application filed December 21, 1917. Serial No. 208,317.

To all whom it may concern:

Be it known that we, Sir ARTHUR TREVOR DAWSON, knight, and Sir GEORGE THOMAS BUCKHAM, knight, both subjects of the King of Great Britain, residing at Vickers House, Broadway, Westminster, in the county of London, England, have invented certain new and useful Improvements Relating to Gun-Carriages, of which the following is

10 a specification.

This invention relates to field gun carriages and has for its object to provide an improved bed plate capable of being sunk into or embedded in the ground and comprising a support for the carriage wheels and a member against which the rear part of the trail bears and upon which it can be moved to traverse the carriage.

According to the invention the bed plate 20 is composed of a rigid structure adapted to support the carriage wheels at or near its forward part and to support the trail at or near its rear part in such a manner as to permit of the carriage being traversed. The 25 said rigid structure is preferably of triangular form and may have at or near its apex a support for the carriage wheels and at or near its base an arc-shaped member for the trail.

30 In order that the said invention may be clearly understood and readily carried into effect we will describe the same more fully with reference to the accompanying drawings, in which:—

35 Figures 1 and 2 are respectively a side elevation and a plan of the improved bed plate with the gun carriage shown by chain lines in position thereon. In Fig. 1 the rear portion of the bed plate is shown in section 40 on the line 1, 1 of Fig. 2.

Fig. 3 is a local section showing the means hereinafter referred to for anchoring the gun carriage to the bed plate.

The triangular structure constituting the 45 bed plate is composed of side members A, A' detachably connected together at their forward ends by means of a removable pin a or otherwise, and a base member A' detachably connected to the rear ends of the 50 side members. These members are composed of wooden beams reinforced where necessary by iron or steel plates. The base member consists as shown of two superposed beams a', a' recessed near their outer ends 55 to accommodate between them the side

beams. The two base beams a', a' are connected together by bolts a², a² and plates A², A² so as to clamp each of the side beams between the base beams. B is the aforesaid arc-shaped member which is constituted by 60 a metal plate attached to the upper one of the base beams and resting at its ends upon the side beams. This plate has a channel for a flange or projection B' on the rear part of the gun carriage trail and is formed 65 with a number of holes for the reception of a locking pin which passes through a hole (or through one or other of two holes) in a plate B² on the trail so as to hold the gun carriage in the desired lateral position. 70 This plate carries the flange or projection B'. C, C are wheel platforms which are constituted by metal plates connected together by transverse beams C', C' which rest upon the forward portions of the side beams A, A. 75 The platform structure thus constituted is prevented from moving forward by angle irons A³, A³ on the side beams, and rearward by wooden blocks A⁴ (Fig. 1) attached to the side beams. The platform structure 80 is also prevented from moving sidewise by plates C², C² which depend from the platforms and bear against the outer surfaces of the said wooden blocks A⁴ attached to the side beams. The said platforms have on 85 their upper surfaces curved angle irons C³, C³ against which the inner sides of the rims of the gun carriage wheels bear during the movement of the trail over the aforesaid arc-shaped member or plate B near the 90 base of the triangular structure. The said curved angle irons have as their center of curvature that of the said arc-shaped member or plate.

The beams and the platform structure are 95 provided with rope gromets as shown so that they can be moved readily from place to place and these gromets are intended to receive hand-spikes a^x, a^x for the purpose of lifting the beams out of the ground. 100

Means may be provided for anchoring the carriage to the platforms C, C in such a manner as to permit of traversing the carriage on the platforms and at the same time preventing the wheels from lifting when 105 the gun is fired. These means are shown in Fig. 3 and comprise a bolt D passing through metal plates D', D² of which the former lies across the rear two of the aforesaid transverse beams C', C' and the other 110

across two blocks, D³, D³ suitably clamped or connected to the said transverse beams. The said bolt has an eye through which passes a chain D⁴ which also passes around 5 the gun carriage axle D⁵, this chain being tightened by a rigging screw or turn-buckle D⁶.

What we claim and desire to secure by Letters Patent of the United States is:—

- 10 1. A bed plate serving as a firing platform for a gun carriage and composed of a rigid structure of triangular form serving to support the carriage wheels at or near its apex and to support the trail at or near 15 its base in such a manner as to permit of the carriage being traversed on the structure.
2. A bed plate serving as a firing platform for a gun carriage and composed of a rigid structure of triangular form having 20 at or near its apex a support for the gun carriage wheels and at or near its base an arc-shaped support for the trail.

3. A bed plate serving as a firing platform for a gun carriage and composed of a rigid structure of triangular form having 25 at or near its apex a support for the gun carriage wheels and at or near its base an arc-shaped support provided with a channel for the reception of a projection of the trail.

4. The combination with a bed-plate 30 serving as a firing platform for a gun carriage and composed of a rigid structure of triangular form having at or near its apex a support for the gun carriage wheels and at or near its base an arc-shaped support 35 for the trail, of means for connecting the carriage to the structure so as to prevent the wheels from lifting when the gun is fired.

In testimony whereof, we affix our signatures.

ARTHUR TREVOR DAWSON.
GEORGE THOMAS BUCKHAM.
